CLAIM

The ornamental design for a wireless e-stop type switching device, as shown and described.

DESCRIPTION

FIG. 1 is a top and left front perspective view of a wireless e-stop type switching device, showing my new design;

FIG. 2 is a top and right rear perspective view thereof;

FIG. 3 is a front elevational view thereof;

FIG. 4 is a rear elevational view thereof;

FIG. 5 is left side elevational view thereof, the right side elevational view being a mirror image of the side view shown;

FIG. 6 is a top plan view thereof; and,

FIG. 7 is a bottom plan view thereof.

The indicia shown in broken line in FIGS. 1, 5 and 7 are for illustrative purposes only and form no part of the claimed design.
